UNITED STATES PATENT OFFICE.

JOHN CLEAVER DIAMENT, OF BRIDGETON, NEW JERSEY.

CAN CLOSURE.

Application filed August 2, 1926. Serial No. 126,601.

My invention relates to new and useful improvements in cans and more particularly to a closure therefor, the principal object of the invention residing in providing the closure with a transparent insert whereby the contents of the can may be viewed.

Another object of the invention resides in the provision of novel means for seating or positioning the transparent insert whereby a tight seal is provided.

A further object of the invention consists in so forming the closure that the transparent insert may be secured therein by rolling, spinning, or dieing the closure.

Still another object of the invention resides in positioning the transparent insert in the closure at such a point that the closure may flex during the canning operation, it being understood that when steam is applied to the cans, the contents within the can will expand thereby forcing the closure outwardly to a certain extent and then when the contents of the can is cooled the same will be contracted and a vacuum will be created within the can thereby causing an inward movement of the closure.

A further object of the invention consists in so forming the closure from one piece of metal that the transparent insert may later be secured thereon by rolling, spinning or dieing the closure.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claim.

In the drawings:

Fig. 1 is a top plan of the closure with the transparent insert in position.

Fig. 2 is a transverse vertical section through the closure and insert.

Figs. 3, 4 and 5 are fragmental sectional details showing the several positions of the parts adjacent the insert, Fig. 3 showing the closure, adjacent the opening for the insert, prior to the positioning of the insert therein, Fig. 4 shows the insert in position and the first step in the bending or rolling process,

and Fig. 5 illustrates the completed rolling to secure the insert in position.

In the drawings 1 indicates one of the end closures of the can which will be secured to the cylindrical body portion, in the usual manner. The end closure is formed of metal which is preferably stamped and in carrying out my invention a central opening 2 is provided to be covered by the transparent insert through which the contents of the can may be viewed. In the initial formation of the closure an inclined flange 3 is formed around the opening 2, and there is an upwardly extending bead 4 formed intermediate the flange 3 and the horizontal body portion 5 of the closure. As illustrated more particularly in Fig. 3 of the drawings the inclined flange 3 is on a plane somewhat lower than the plane of the horizontal portion 5. With the closure initially stamped as shown in Fig. 3 gasket material 6 is placed upon the flange 3 and the transparent plate or insert 7 is seated upon the material as more particularly illustrated in Fig. 4. The upwardly extending bead 4 is then rolled, spun or die'd to assume the position illustrated in Fig. 4 and is finally pressed down to assume the horizontal position disclosed in Fig. 5 to overlie the upper surface of the insert 7. It will thus be seen that the beaded portion 4 which has been pressed into the position shown in Fig. 5 will hold the transparent insert in tight engagement with the gasket material 6. A hermetical seal is formed between the closure and the insert.

As stated I preferably have the flange 3 extending upwardly at an angle and when thus formed the end of the flange will engage the gasket material 6 as shown more particularly in Figs. 2, 4 and 5 of the drawings and prevent the gasket material from being drawn from its seat when a vacuum is created within the can. However, if desired, the flange may be formed to extend in a horizontal position as distinguished from the inclined position shown. The gasket material will also be passed around the edge of the transparent insert as shown.

It will be understood that there are two end closures for each can and my transparent insert may be provided in either the top or bottom closure as may be desired. The insert is securely held in position and a tight seal is provided between the closure plate and the insert. In commercial canning operations

the product is placed in the cans in a raw state and after the can is sealed it is placed in boiling water or steam and cooked for various periods of time depending upon the particular product canned. This cooking process expands the contents of the can and the end closures are swelled due to the internal pressure within the can. When the can and its contents are allowed to cool the contents contract and a vacuum is created within the can. By positioning my transparent insert away from the outer edge of the closure there is sufficient metal between the outer edge of the closure and the insert to allow a flexing of the closure, this flexing allowing for the outer swelling of the closure during the cooking operation, and the drawing in of the closure when the vacuum is created within the can. The transparent insert must be so securely held as to prevent a breaking of the seal when the vacuum is created within the can. In securing the insert in the closure as I have illustrated and described the same is securely held so that the insert will not be broken during the cooking operation or by the vacuum

created in the can after the cooling has taken place and a tight seal will always be provided to prevent leakage or spoilage of the contents within the can.

Having fully described my invention what I claim as new and desire to secure by Letters Patent is:

A can closure formed with an opening therein, a portion of the closure adjacent the opening being depressed inwardly from the normal outer face of the closure to form a relatively wide inwardly directed and upwardly inclined seat surrounding the opening, a gasket received on the seat, a transparent insert received on the gasket, and a portion of the closure adjacent the depressed portion and the periphery of the insert being depressed over the outer face of the insert to force the insert into tight engagement with the gasket and to compress the gasket into tight engagement with the seat.

In testimony whereof I hereunto affix my signature.

JOHN CLEAVER DIAMENT.
